(57)

CLAIM

The ornamental design for a duct puller, as shown and described.

DESCRIPTION

FIG. 1 is a perspective view of the duct puller of my new design.

FIG. 2 is a bottom plan view thereof.

FIG. 3 is a top plan view thereof.

FIG. 4 is a left side elevational view thereof. The right side elevational view is a mirror image thereof.

FIG. 5 is a front elevational view thereof; and,

FIG. 6 is a back elevational view thereof.

1 Claim, 3 Drawing Sheets(56)
